United States Patent Office

Des. 212,410
Patented Oct. 15, 1968

212,410

JUG

Richard L. Platte, Ann Arbor, Mich., assignor to Hoover
Ball and Bearing Company, Saline, Mich., a corpora-
tion of Michigan

Filed Dec. 18, 1967, Ser. No. 9,837

Term of patent 14 years

(Cl. D9—39)

FIG. 1

FIG. 2

FIG. 3

FIG. 4

FIG. 5

FIGURE 1 is a side elevational view of a jug, showing my new design;

FIGURE 2 is a rear elevational view;

FIGURE 3 is an elevational view taken at an angle of 135° to the left of FIG. 1;

FIGURE 4 is a top plan view; and

FIGURE 5 is a section taken on the line 5-5 of FIGURE 1.

The dominant features of my new design reside in the portions shown in full lines.

I claim:

The ornamental design for a jug, substantially as shown and described.
